UNITED STATES PATENT OFFICE.

THOMAS O'BOYLE, FRANK O'BRIEN, AND JAMES RYAN, OF MCGILL, AND BERT THAYER, OF ELY, NEVADA.

HYDRAULIC ORE-SEPARATOR.

1,056,293.

Specification of Letters Patent.

Patented Mar. 18, 1913.

Application filed January 16, 1912. Serial No. 671,415.

To all whom it may concern:

Be it known that we, THOMAS O'BOYLE, FRANK O'BRIEN, and JAMES RYAN, residing at McGill, and BERT THAYER, residing at 5 Ely, both in the county of White Pine and State of Nevada, citizens of the United States, have invented certain new and useful Improvements in Hydraulic Ore-Separators; and we do hereby declare the following 10 to be a full, clear, and exact description of the invention, such as will enable others skilled in the art to which it appertains to make and use the same, reference being had to the accompanying drawings, and to the 15 letters and figures of reference marked thereon, which form a part of this specification.

This invention relates to new and useful 20 apparatus for separating precious metals from sands, etc., and consists in the provision of hydraulic apparatus for saving the floating gold.

More specifically the invention comprises 25 an apparatus having a series of slotted tables arranged one above another and through the slots of which the water under pressure is introduced to cause the lighter values to be separated from coarser material and to cause an accelerated current to carry 30 away the lighter values before being given a chance to settle, thereby effecting an appreciable saving over hydraulic separating apparatus commonly employed and in which the floating gold is usually not recovered.

35 Our invention comprises an apparatus having various details of construction and combinations and arrangements of parts which will be hereinafter fully described, shown in the accompanying drawings and 40 then specifically defined in the appended claim.

We illustrate our invention in the accompanying drawings, in which:—

Figure 1 is a side elevation of an apparatus 45 embodying the features of our invention. Fig. 2 is a cross sectional view on line 2—2 of Fig. 1, and Fig. 3 is a sectional view on line 3—3 of Fig. 1.

Reference now being had to the details of 50 the drawings by letter, A designates a sluice way or trough having a series of horizontally-disposed tables B which are disposed in step relation with one another, and each

table is supported at its ends by an inclined wall C, the lower ends of the inclined walls 55 being spaced apart and connected by a transverse partition D. Each of said tables is provided with one or more elongated slots E running the entire length of the table and which slots are disposed at inclinations to 60 each other and the walls of the slots are slightly wider at their lower ends than at the upper ends. It will be noted that in the upper tables a single slot is formed in the table and said tables, preferably, are slightly 65 narrower than the tables in which there may be a plurality of the slots, a single slot being sufficient in the upper tables to carry away the coarser materials being separated, the major part of which will have passed 70 through the slots in the lower tables before reaching the higher ones. Said sluice way or trough is provided with an opening K through which the material is fed into one end thereof where it is acted upon by the water 75 being forced into the trough. Passing through each horizontal partition D is a pipe N through which water is introduced under pressure into each chamber beneath the table and affords means whereby water 80 at a uniform pressure may be introduced to act upon the material and produce a current which will tend to carry the lighter values toward the upper portion of the trough or sluice way before they have an 85 opportunity to settle with the heavier particles.

Each partition D is provided with an exit pipe O which may be temporarily closed by means of a plug O' and affording means 90 whereby the heavier particles which have settled may be withdrawn from said chambers.

In operation, when water at a uniform pressure is forced into the various compartments and up through the slots in the tables, an upper current will be caused, the current being accelerated as the water is forced up through the various tables, the heavier particles being precipitated while the floating 100 gold will be carried forward and upward and not allowed to settle with the heavier materials.

By the provision of an apparatus as shown and described, we have found that it 105 is possible to save a large proportion of the

lighter values which are commonly not recovered, owing to their being precipitated by the heavier particles of the sand or gravel.

What we claim to be new is:—

- 5 An apparatus for separating floating gold from sand and gravel comprising a sluice way having a hydraulic compartment, the opposite walls of which are inclined relative to each other and having inlet and exit
- 10 pipes leading into the compartment, a table extending between the inclined walls and having deep elongated slots at inclinations to each other and extending the entire length of the table, thereby affording means where-
- 15 by a nozzle effect may be imparted to a cur-

rent of water passing up through and serving to separate the slimes and light materials from the heavier particles of the minerals being treated, as set forth.

In testimony whereof we hereunto affix 20 our signatures in the presence of two witnesses.

THOS. O'BOYLE.
FRANK O'BRIEN.
JAS. RYAN.
BERT THAYER.
